UNITED STATES PATENT OFFICE.

HUGH R. BLACK, OF HALL, NEW YORK.

ART OF PACKAGING FRUIT AND THE LIKE.

Application filed December 27, 1923. Serial No. 683,015.

To all whom it may concern:

Be it known that I, HUGH R. BLACK, a citizen of the United States of America, residing at Hall, in the county of Ontario and ⁵ State of New York, have invented certain new and useful Improvements in the Art of Packaging Fruit and the like, of which the following is a specification.

This invention relates to new and useful ¹⁰ improvements in the art of packaging fruit and the like and has particular reference to the settling of fruit and the like into proper transportable condition in suitable containers.

¹⁵ In packing fruit, such as apples, it is the present custom to employ settling platforms upon which the shipping containers are placed while they are being filled.

I am familiar with the various different ²⁰ types of settling platforms disclosed in the art, but none of these platforms are especially adapted for such work due to the fact that the different mechanisms employed for actuating the platforms are not controllable ²⁵ for permitting the intensity of the jolts produced to be varied. Such a control is desirable, as will appear at a later point. These settling platforms are usually arranged to be driven from a single shaft and are preferably directly connected thereto. With such an arrangement, it will be seen that all of the platforms are operated in unison. The most common mechanism employed for actuating such platforms, and it might be ³⁰ well to note that all of the different types of mechanism now in use possess the same disadvantages, consists of a common drive shaft and an individual cam for each platform keyed to said shaft. These cams ³⁵ usually bear directly against the under surface of the movable platform and after the highest portion of the cam has passed under the platform, the latter is dropped upon a rigid support which is usually the floor.

⁴⁰ The dropping of the platforms produce the jolts that are employed for settling the fruit in their containers. It will be seen by this arrangement that as soon as a container is placed upon a platform it starts receiving jolts and the jolting continues until the container is removed.

Barrels are usually employed as containers for transporting apples. Before they are placed upon the settling platforms to be ⁴⁵ packed, the bottom of each is provided with

a "facer" which consists of a layer of the best or selected apples placed in substantially concentric circles with the stems down. The barrels so prepared are then placed upon the platforms. As has been stated, ⁶⁰ with the types of settling platforms now in use, the barrels and containers are immediately subjected to jolts. Such jolting of the apples at this stage of the operation is objectionable as it has a tendency to dislodge ⁶⁵ the fruit forming the "facer". This objection cannot be overcome with the present types of settling platforms.

As the packing operation proceeds, the barrels on the platforms are filled by dumping basketsful of apples thereinto. It will be apparent, to those skilled in the art, that a barrel having a "facer" and one basketful of apples therein should not receive and ⁷⁰ does not require as severe a jolt to settle the fruit as a barrel more nearly filled. However, the present types of platforms do not permit adequate adjustment or reduction of the intensity of the jolt at this time, nor in fact, do they permit an adequate adjustment at any time. ⁷⁵

During a day's operation, it often happens that the supply of unpacked apples at a particular settling platform will be exhausted and a new supply will not be immediately ⁸⁰ furnished. It, also, often happens that a partially filled barrel will be on this particular platform when the supply is exhausted. If this partially filled barrel is left upon the platform and its contents subjected to jolts for a relatively long time, the apples ⁸⁵ will be in danger of being bruised. With the present types of settling platforms, it becomes necessary to remove the partially filled barrel until a new supply of unpacked ⁹⁰ apples is furnished.

In reference to the intensity of the jolts produced by the settling platforms disclosed in the art, it is admitted that there is a certain amount of variation in such intensity ¹⁰⁰ during the loading of a barrel. In considering the cam operated type, it will be seen that the platform is elevated during the operation of the cam to a predetermined, never-varying height from which it is dropped. By considering that this height is equal to one foot, for the purpose of simplifying the explanation, it will be seen that if a barrel and its contents weighing one pound is dropped from the height of one foot, it will ¹⁰⁵ ¹¹⁰

receive a jolt equal in intensity or energy to one foot-pound. If the barrel and its contents weighs five pounds and the same are dropped from the aforementioned height, the energy or intensity of the jolt will equal five foot-pounds, etc. This use of a well settled rule of gravity is the only means than can be employed in the present type of settling platforms for varying the intensity of the jolt applied to the apples being packed.

It is an important object of this invention to provide a method of packing fruit and the like, wherein the contents of the container are caused to settle into transportable condition by an intermittent jolting action applied to the container during filling of the same.

A further object of the invention is to provide a settling platform having means for operating the same which is controllable for producing jolts of different intensity.

A further object of the invention is to provide a settling platform having means for operating the same in such a manner that the platform will be moved while unloaded but will not be subjected to a jolting action.

A further object of the invention is to provide a settling platform adapted to produce a jolting action for performing its required work but the jolting action will not start until a predetermined load has been placed upon the platform.

A further object of the invention is to provide a settling platform which performs its work by providing a jolting action and is constructed in such a manner that the intensity of the jolt produced thereby will be increased progressively in proportion to the increase in load weight placed thereon.

A further object of the invention is to provide a settling platform of the above mentioned type which is provided with means for increasing or decreasing the intensity of the produced jolt during operation under load and for preventing the production of any jolt, while loaded, if not desired.

A still further object of the invention is to provide an apparatus for producing jars or jolts which are communicated to a load carried thereby, and the apparatus is of such a construction that the intensity of the jars or jolts will increase in proportion to the increase of load placed thereupon, the jarring or jolting action being produced by dropping the load onto a rigid support, and the increase in the intensity of the jars or jolts being produced by automatically dropping the load from increasing heights with the heights increasing proportionately with the increase in the load.

In the accompanying drawings forming a part of this specification and in which like

numerals are employed to designate like parts through the same,

Figure 1 is a side elevational view, partly in section, of the settling platform embodying this invention, 70

Figure 2 is a transverse sectional view, partly in plan view, taken upon line II—II of Fig. 1,

Figure 4 is a fragmentary elevational view of a portion of the mechanism embodying this invention,

Figure 5 is a fragmentary sectional view taken upon line V—V of Fig. 4, 80

Figure 6 is a fragmentary elevational view of a drive shaft and an eccentric which is employed for operating the mechanism,

Figure 7 is a sectional view, partly in elevation, of Fig. 6, 85

Figure 8 is a diagrammatical view of the apparatus embodying this invention taken at one stage of its cycle of operation,

Figure 9 is a similar view to Fig. 8 and shows the apparatus at a later stage, 90

Figure 10 is a view similar to Figs. 8 and 9 and shows the apparatus at a still later stage,

Figure 11 is a diagrammatical view of the apparatus and shows one stage during the operation of the same while the platform is unloaded, and 95

Figure 12 is an elevational view of a simple, manually operable apparatus which embodies the same principles of operation as the preferred type of apparatus illustrated in Figs. 1 to 11 inclusive.

The principles embodied in this method of packaging fruit and the like may be clearly and easily described by referring to the simple, manually operable apparatus illustrated in Fig. 12. In this figure, the character G illustrates the ground upon which is mounted a bracket 5 which is adapted for having pivotally secured thereto, as at 6, a platform 7 which is provided with a spacing block 8 depending therefrom. It will be seen that this spacing block 8 positions the outer free end 7^a of the platform a suitable distance from the ground for permitting the roller 9 carried by the outer, lower end of the substantially L-shaped lever 10 to be placed therebeneath. This L-shaped lever 10 is provided with a pair of depending, spaced legs 11 to which is rotatably secured a wheel 12.

The operation of this apparatus is as follows:—

When a barrel is placed upon the platform 7 and is in a condition to be packed with fruit or the like, the roller 9 may be moved under the projecting end 7^a of the platform and the substantially L-shaped lever 10 pivoted upon its fulcrum point or point of engagement with the ground G which consists 125

of the wheel 12. The pivoting of this lever 10 into its dotted line position will elevate the platform 7 and the container placed thereupon to the elevation shown in dotted lines. If the lever 10 is moved so that the roller 9 will be disengaged from the end 7^a of the platform 7, the said platform will be allowed to drop until the spacing block 8 strikes the ground G. The container and its 10 contents will receive a jolt when the platform strikes the ground G. If the lever 10 is again positioned with the roller 9 in engagement with the undersurface of the projecting end of the platform 7 and the platform 15 is elevated to a greater height than that shown in dotted lines, the removal of the lever 10 will cause the platform and the object placed thereupon to receive a jolt of increased intensity when the spacer block 8 20 strikes the floor line G. It will be seen that the intensity of the jolt produced may be increased or decreased, as desired, by varying the height at which the platform is dropped. It will be noted that this increase or decrease 25 in the intensity of the jolt is supplemental to the increase of the intensity of the jolt produced by increasing the weight of the object placed upon the platform.

The preferred type of apparatus for 30 mechanically performing the operation of packaging fruit is illustrated in Figs. 1 to 7 inclusive. The character F illustrates a section of a floor upon which the platform P is placed and to which it is pivotally 35 connected by means of the hinge 13.

It is to be understood that these settling 40 platforms are generally provided in suitable numbers to handle the amount of business possessed by the particular packing house within which they are employed. They are also arranged so that a single drive shaft may be employed for operating a suitable number of the same.

The section of shafting 14 is rotatably 45 supported, by any suitable means, so that the same will extend transversely of the platform and will be related thereto as shown in Figs. 1 and 2. Suitably keyed to the shaft 14 is an eccentrically mounted 50 wheel 15 which is substantially enclosed by the collar member 16 and is retained therein by means of the removable annular ring 17, as best illustrated in Figs. 6 and 7. In Fig. 7, there are shown anti-friction rollers 55 18 which are positioned between the periphery of the wheel 15 and the inner annular face of the collar member 16. This collar member 16 is provided with a boss 19 projecting radially from its periphery, as illustrated. Suitably connected to the boss 60 19 and extending axially therefrom is a rod 20 which is provided with a threaded outer end 21 to which is adjustably secured the angular yoke member 22. This yoke member 22 is adapted for being retained in dif-

ferent adjusted positions in respect to the rod 20 by means of the lock nut 23.

Pivotedly connected to the outer spaced ends 24 of this angular yoke 22 is a connector 25 which consists of a pair of crossed, 70 integrally formed, offset tubular members 26 and 27. The tubular member 26 is directly pivotally connected to the said free ends 24 of the angular yoke 22 by means of the rivet or pivot-pin 28. Longitudinally 75 adjustably connected to the tubular member 27 is a rod 29 which is of substantially twice the length of the rod 20 and extends downwardly to be pivotally connected to the projecting tongue P' of the platform P. It will 80 be seen that the upper end 30 of this rod 29 is externally screw threaded for receiving the lock nuts 31 which are employed for adjustably connecting the tubular portion 27 of the connector 25 to the said rod 85 29. It further will be seen that this rod 29 is provided, substantially midway of its length, with an offset arcuate portion 32 which is positioned in horizontal alinement with the eccentric connection between the 90 rod 20 and the shaft 14, as best illustrated in Fig. 1.

Suitably secured to the rod 29 and projecting laterally horizontally therefrom is 95 an arm 33 having a cross piece 34 at its outer end to the outer ends of which are secured the springs 35. The rod 20 is provided, in horizontal alinement with the arm 33, with a pair of vertically spaced laterally extending arms 36 which act as guides for the plate 37 slidably connected thereto. Centrally positioned between these guiding arms 36 and extending in parallelism therewith, there is provided a feeding screw 38 which is rotatably connected to the rod 20 100 and is threadedly connected to the plate 37. This feed screw 38 is further provided with an operating handle 39 by means of which it can be rotated in either direction as desired. The free ends of the plate 37 are 105 connected to the free ends of the springs 35 in the manner best illustrated in Figs. 1 and 3. It will be seen that these various elements provide an adjustable, yieldable connection between the rods 20 and 29 at a 110 point spaced below their point of pivotal connection.

In Figs. 1 and 2 there is shown a standard or upright 40 which is positioned laterally of the tongue P' of the platform P and terminates a suitable distance below the drive shaft 14. Horizontally adjustably secured to the upper end of this upright or standard 40 is an angle plate 41 which is provided with a rotatable roller 42 having its axis extending horizontally. As shown in Figs. 1 and 2, this roller 42 is positioned against or slidably engages the lower portion of the rod 29.

In Figs. 1 and 2, there is shown in dotted

line what is intended to represent a container B which in this particular illustration consists of a barrel. This barrel B and its contents, not shown, constitutes the object or objects which is to be operated upon by this apparatus.

The operation of this apparatus is as follows:—

By first considering the apparatus without 10 a load on the platform, as illustrated in Fig. 11, it will be understood that the rotation of the shaft 14 in a clockwise direction, as indicated by the arrow in this figure, the eccentric block 15 will be caused to rotate in the 15 same direction. When the eccentric 15 is positioned in dead center with the major portion of the eccentric below the shaft 14, the platform P will be positioned in engagement with the floor F. As the eccentric 20 travels with the shaft, the major portion of the same, after traveling ninety degrees of a circle, will be positioned to the left of the shaft 14, when viewed from the end visible in this figure and the rods 20 and 29 will 25 have been moved perpendicularly one-half the distance of their total distance of upward movement. The platform P will have been moved in a similar manner. It will be understood that on account of the connection 30 between the rods 20 and 29, furnished by the springs 35, the said rods will be retained in substantially parallel relation with respect to each other. The eccentric will have been moved into engagement with the arcuate off- 35 set portion 32 of the rod 29 and the said rod will have been moved away from the roller 42 until it extends perpendicularly. As the shaft 14 continues to rotate, the eccentric will travel therewith and after having 40 traveled an additional ninety degrees of a circle, the major portion of the eccentric will be positioned on a dead center above the shaft 14. It will be understood that the rods 20 and 29 and the platform P have then been 45 moved to their limits of movement in an upward direction. It must be remembered that the springs 35 are drawing the rods 20 and 29 toward each other and that the point at which this drawing action is occurring is 50 positioned below the point of pivotal connection, 28, between these said rods. With the major portion of the eccentric positioned on dead center above the shaft 14, the lower portion of the rod 29 will have been moved 55 into engagement with the roller 42. As the shaft 14 continues to rotate in a clockwise direction, for an additional one-quarter of a complete revolution, the eccentric will be positioned as shown in Fig. 11 and the rods 60 20 and 29, with the platform P, will have been moved downwardly one-half the distance of their total movement in the direction toward the floor F. During this quarter of a turn of the shaft 14, the upper portion 65 of the rod 29 and the entire length of the

rod 20 will have been moved out of parallelism and into an acute angle in respect to each other. This acute angle is created or caused by the roller 42 which prevents the upper portion of the rod 29 from following 70 the lateral movement of the rod 20, this acute angle continues to increase until it reaches its maximum which occurs when all of the elements are in their respective positions as illustrated in Fig. 11. As the shaft 75 14 and eccentric wheel 15 continue to rotate, the eccentric will reach its starting point with the major portion of the same on the dead center below the shaft 14. At this time the platform P will have been moved into engagement with the floor F. It will be noted that the platform has merely been pivoted upwardly and then downwardly and that no jolting of the same has occurred.

The apparatus has been illustrated in 80 Figs. 1 and 8 to 10 inclusive with a load positioned upon the platform. For tracing the cycle of operation of the various elements under load, Figures 8 to 10 inclusive 85 will be referred to. Figure 8 shows the platform P resting upon the floor F and also shows the eccentric wheel 15 on dead center below the shaft 14. As the shaft rotates in the direction of the arrow in Figs. 8 to 10 inclusive, the major portion of the eccentric will move upwardly on the side of the shaft toward the rod 29. The eccentric will move the rod 29 into a true vertical position and the springs 35 will retain the rod 20 and the upper portion of the rod 29 in 90 parallelism during their upward movement. As the shaft 14 and eccentric wheel 15 continue to rotate, the latter will be positioned with its major portion above the shaft 14 after the latter has made an additional quarter of a turn. It will be noted at this point that as the shaft continues to rotate, the eccentric will be moved around the shaft in the direction of the arrow and the lower portion of the rod 29 will be moved into engagement with the roller 42. The lateral movement of the rod 29 then ceases, but the rod 20 continues to move laterally. It will be apparent that the rods are then moved 100 out of parallelism and that an acute angle 105 will be formed therebetween. The springs 35, however, will still be exerting a force to draw the rods together. As soon as this acute angle is formed, it will be apparent 110 that the rod 20 is exerting an upward lateral pushing force upon the rod 29. There is now two forces working opposite to each other, to wit: the load upon the platform P pulling downwardly upon the rod 29 in an endeavor to cause the rod 20 to pivot in 115 respect to the shaft 14 and eccentric 15 for permitting the platform and its load to be dropped onto the floor and the springs 35 exerting a pulling force between the rods 20 and 29 to retain them in parallel positions 120 125 130

- in respect to each other. As the eccentric 15 continues to travel around the shaft 14, the acute angle between the upper portion of the rod 29 and the rod 20 will be increased. 5 It will be apparent that as this acute angle increases, the strain upon the springs 35 will be increased and the downward pull of the weighted platform will be aided. The downward movement of the eccentric 15 will 10 continue to gradually lower the rods 20 and 29 and the weighted platform P until the weight of the platform, aided by the ever increasing acute angle between the upper portion of the rod 29 and the rod 20, overcomes 15 the pulling force of the springs 35. When this occurs, the rods will snap over, as illustrated in Fig. 10 and the platform will be dropped onto the floor. This dropping of the loaded platform will produce a jolt 20 which will be transmitted to the object thereupon. As the shaft continues to rotate the various elements will be returned to their respective positions, as illustrated in Fig. 25 8, and the second cycle of operation will occur.

The essential points to be noted in connection with the operation of this apparatus are as follows:—

It will be noted that the platform is 30 always lifted to a predetermined height and after reaching this height it starts to descend. The acute angle between the rods 20 and 29 does not start to occur until the platform starts to descend. The dropping 35 of the platform always occurs at some point during its descent.

As has been described, the platform will be gradually lowered until the weight of the same overcomes the force of the springs 35 whereupon the platform will be dropped 40 rapidly and will receive a jolt as it strikes the floor. It will be apparent from these facts that as the platform is raised and lowered, receiving a jolt when it is lowered, 45 by increasing the weight on the platform, the springs will be overcome at increasing heights and the jolts received by the platform will increase in intensity in proportion to the increasing height at which the platform 50 is dropped.

By increasing the tension of the springs 35, it will be apparent that a greater load will be required to overcome the same. Therefore, the jolting action can be stopped, 55 notwithstanding the load upon the platform, by placing a sufficient tension upon the springs 35.

It is now believed that the construction 60 and operation of the apparatus set forth in Figs. 1 to 11 inclusive will be understood by those skilled in the art. It will be apparent that the movement of the rods 20 and 29 may be used for other purposes than operating a settling platform. For instance, the 65 movement of the rod 29 might be utilized

for intermittently opening and closing a valve of the Poppet type, the opening movement being gradual while the closing movement will be very rapid. It is believed that this brief suggestion as to the possibilities 70 of utilizing the movement of the various elements for different purposes will be apparent without suggesting any further adaptations.

It is to be understood that the forms of this invention herewith shown and described 75 are to be taken as preferred examples of the same, and that various changes in the shape, size, and arrangement of parts may be resorted to without departing from the spirit 80 of the invention or the scope of the subjoined claims.

Having thus described the invention, I claim:—

1. The method of producing a graduated settling action of the contents of a container 85 during filling of the latter, which method consists in producing impacting movements which vary in extent in successive stages.

2. The method of producing a graduated settling action of the contents of a container 90 during filling of the latter, which method consists in producing impacting movements which vary in extent in accordance with the increasing load.

3. The method of producing a graduated settling action of the contents of a container 95 during filling of the latter, which method consists in producing impacting movements which are repeatedly increased in extent 100 over all previous movements.

4. The method of producing a graduated settling action of the contents of a container during filling of the latter, which method 105 consists in producing impacting movements which increase in extent, in accordance with the increasing load.

5. The method of producing a graduated settling action of the contents of a container during filling of the latter, which method 110 consists in producing impacting movements of the container which progressively increase in extent.

6. The method of producing a graduated settling action of the contents of a container during filling of the latter, which method 115 consists in producing impacting movements of the container which vary in extent in accordance with the increasing load.

7. The method of producing a graduated settling action of the contents of a container during filling of the latter, which method 120 consists in producing intermittent impacting movements which commence when the container has received a predetermined portion of its intended load and which vary in extent until the container receives its full load.

8. The method of producing a graduated settling action of the contents of a container 125 during filling of the latter, which method 130

consists in producing intermittent impacting movements which commence when the container has received a predetermined portion of its intended load and which vary in 5 extent, until the container receives its entire load, in accordance with the increasing load.

9. In the packaging of fruit and the like, wherein the contents of the container are caused to settle into transportable condition 10 by a succession of jolts applied to the container during filling of the latter, and wherein the jolting action is provided by moving the container support upwardly out of a normal position and permitting it to drop 15 to its normal position, the method of producing a graduated settling action of the contents, said method consisting in varying the intensity of the applied jolt as the filling proceeds by varying the distance through 20 which the support drops.

10. In the packaging of fruit and the like, wherein the contents of the container are caused to settle into transportable condition by a succession of jolts applied to the 25 container during filling of the latter, and wherein the jolting action is provided by moving the container support upwardly out of a normal position and permitting it to drop to its normal position, the method of producing a graduated settling action of the 30 contents, said method consisting in increasing the intensity of the applied jolt as the filling proceeds by progressively increasing the distance through which the support 35 drops.

11. In the packaging of fruit and the like, wherein the contents of the container are caused to settle into transportable condition by a succession of jolts applied to 40 the container during filling of the same, the method of producing a graduated settling action of the contents, said method consisting of varying the intensity of the applied jolt as the filling proceeds, the intensity 45 variations being varied from those resulting from the normal variations produced by weight in the filling operation.

12. In the packaging of fruit and the like, wherein the contents of the container are 50 caused to settle into transportable condition by a succession of jolts applied to the container during the filling of the same, the method of producing a graduated settling action of the contents, said method consisting in increasing the intensity of the jolt 55 as the filling proceeds, the intensity increases being varied from those resulting from the normal variations produced by weight in the filling operation.

60 13. In the packaging of fruit and the like, wherein the contents of the container are caused to settle into transportable condition by a succession of jolts applied to the container during filling of the same, the method 65 of producing a graduated settling action of

the contents, said method consisting in progressively increasing the intensity of the jolt as the filling proceeds, the intensity increases being varied from those resulting from the normal increases produced by 70 weight in the filling operation.

14. In the packaging of fruit and the like, wherein the contents of the container are caused to settle into transportable condition by a succession of jolts applied to the 75 container during filling of the same, the method of producing a graduated settling action of the contents, said method consisting in varying the intensity of the applied jolt proportionately with the variation in 80 weight of the content, the intensity variations being varied from those resulting from the normal variations produced by weight in the filling operation.

15. In the packaging of fruit and the like, 85 wherein the contents of the container are caused to settle into transportable condition by a succession of jolts applied to the container during filling of the same, the method of producing a graduated settling action of 90 the contents, said method consisting in increasing the intensity of the applied jolt proportionately to the increase in weight of the content, the intensity increases being varied from those resulting from the normal 95 increases produced by weight in the filling operation.

16. In the packaging of fruit and the like, wherein the contents of the container are caused to settle into transportable condition 100 by a succession of jolts applied to the container during filling of the same, the method of producing a graduated settling action of the contents, said method consisting in progressively increasing the intensity of the 105 applied jolt proportionately with the progressive increase in the weight of the content present during the jolting, the intensity increases being varied from those resulting from the normal increases produced by 110 weight in the filling operation.

17. In a device of the class described, a supporting member, a load bearing member pivotally connected at one end thereto, and means connected to the free end of the load bearing member for raising said end in respect to the supporting member and for dropping the said end onto the supporting member from varying elevations for producing jolts of different intensity. 115

18. In a device of the class described, a supporting member, a load bearing member pivotally supported thereby and adapted to have its load weight increased during operation, and means connected to said members for raising the load bearing member in respect to the supporting member and for dropping the load bearing member onto the supporting member from varying elevations for producing jolts of different 125 130

intensity, the elevation from which said dropping starts being governed by the variations in load weight.

19. In a fruit settling apparatus, a support, a platform pivotally supported thereby, a drive shaft, a pair of rods pivotally connected in series and pivotally connected to said platform, resilient means connecting said rods intermediate their ends, and means for connecting said shaft to one of said rods for causing said platform to operate when said shaft is rotated.

20. In a fruit settling apparatus, a support, a platform pivotally supported thereby, a drive shaft, a pair of rods pivotally connected at their adjacent ends, means for yieldably holding said rods in parallelism with each other, means for pivotally connecting one of said rods to said platform, and means for connecting the other of said rods to said shaft in such a manner that the rotation of said shaft will cause said platform to oscillate.

21. In a fruit settling apparatus, a support, a platform pivotally supported thereby, a drive shaft, a pair of rods pivotally connected at their adjacent ends, means for pivotally connecting one of said rods to said platform, and means for connecting the other of said rods to said shaft in such a manner that the rotation of said shaft will cause said platform to be raised and lowered in respect to said support.

22. In a fruit settling apparatus, a support, a platform pivotally supported thereby, a drive shaft, a pair of rods pivotally connected at their adjacent ends, means for yieldably holding said rods in parallelism with each other, means for pivotally connecting one of said rods to said platform, and means for connecting the other of said rods to said shaft in such a manner that the rotation of said shaft will cause said platform to be raised from and dropped onto said support for producing a jolting action.

23. In a fruit settling apparatus, a support, a platform pivotally supported thereby, a drive shaft, a pair of rods pivotally connected at their adjacent ends, means for yieldably holding said rods in parallelism with each other, means for pivotally connecting one of said rods to said platform, and means for connecting the other of said rods to said shaft in such a manner that the rotation of said shaft will cause said platform to be raised from said support and dropped onto said support from different elevations, the elevations from which said platform is dropped being governed by the load weight on said platform.

24. In an apparatus, a rod, an element connected to one end of said rod, a second rod connected to the first mentioned rod at a point spaced from its connection with said element and extending in the same direc-

tion therewith, a rotatable shaft, and means connecting said shaft to the second rod for causing rotation of said shaft to move said element in opposite directions thru a given path.

25. In an apparatus, a rod, an element connected to one end of said rod, a second rod extending in the same direction as the first mentioned rod, means for adjustably and pivotally connecting one end of the second rod to the free end portion of the first mentioned rod, a rotatable shaft, and means connecting said shaft to the free end of the second rod for causing rotation of said shaft to move said element in opposite directions thru a given path.

26. In an apparatus, a rod, an element connected to one end of said rod, a second rod connected to the first mentioned rod at a point spaced from its connection with said element and extending in the same direction therewith, means for yieldably drawing the intermediate portions of said rods toward each other, a rotatable shaft, and means connecting said shaft to the second rod for causing rotation of said shaft to move said element in opposite directions thru a given path.

27. In an apparatus, a rod, an element connected to one end of said rod, a second rod extending in the same direction as the first mentioned rod, means for adjustably and pivotally connecting one end of the second rod to the free end portion of the first mentioned rod, means for yieldably drawing the intermediate portions of said rods toward each other, a rotatable shaft, and means connecting said shaft to the free end of the second rod for causing rotation of said shaft to move said element in opposite directions thru a given path.

28. In a fruit settling apparatus, a support, a platform pivotally supported thereby, a drive shaft, a pair of rods pivotally connected in series and pivotally connected to said platform, adjustable resilient means connecting said rods intermediate their ends, and means for connecting said shaft to one of said rods for causing said platform to operate when said shaft is rotated.

29. In a fruit settling apparatus, a support, a platform pivotally supported thereby, a drive shaft, a pair of rods pivotally connected at their adjacent ends, means for yieldably holding said rods in parallelism with each other, means for varying the tension of said yieldable holding means, means for pivotally connecting one of said rods to said platform, and means for connecting the other of said rods to said shaft in such a manner that the rotation of said shaft will cause said platform to oscillate.

30. In a fruit settling apparatus, a support, a platform pivotally supported thereby, a drive shaft, a pair of rods pivotally

connected at their adjacent ends, adjustable means for yieldably holding said rods in parallelism with each other, means for pivotally connecting one of said rods to said platform, and means for connecting the other of said rods to said shaft in such a manner that the rotation of said shaft will cause said platform to be raised from and dropped onto said support for producing a jolting 10 action.

31. In a fruit settling apparatus, a support, a platform pivotally supported thereby, a drive shaft, a pair of rods pivotally connected in series and pivotally connected 15 to said platform, a pair of springs connecting said rods intermediate their ends, means for varying the tension of said springs, and

means for connecting said shaft to one of said rods for causing said platform to operate when said shaft is rotated. 20

32. In a fruit settling apparatus, a support, a platform pivotally supported thereby, a drive shaft, a pair of rods pivotally connected at their adjacent ends, means for yieldably holding said rods in parallelism 25 with each other, means for pivotally connecting one of said rods to said platform, an eccentric on said shaft, and means for connecting the other of said rods to said eccentric for causing rotation of said shaft 30 to pivot said platform.

In testimony whereof I affix my signature.

HUGH R. BLACK.
